(57) **CLAIM**

The ornamental design for a laundry drying apparatus as shown and described.

DESCRIPTION

1. Laundry drying apparatus

1.1: a top perspective view;

1.2: an end view;

1.3: a side view;

1.4: a top view;

1.5: a bottom perspective view;

1.6: a bottom view; and

1.7: A partial enlarged view.

This is the product design of a laundry drying apparatus; The top of the appliance has six openings, which are covered with wire mesh; the outer edges are slightly elevated; On the bottom of the appliance there are 6 openings covered with wire mesh as well; There are also four feet, which are hidden behind the housing cover; There is one fan located between each two opposite covered openings; When switched on, the fans rotate and blow air upwards; This air circulation is intended to dry the laundry faster.

In the drawings, the broken lines are shown for illustrative purposes only and form no portion of the claimed design.

1 Claim, 7 Drawing Sheets
